DISPENSING TOP

Woodrow S. Wilson, Altadena, Calif., assignor to Polytop Corporation, Slatersville, R.I., a corporation of Massachusetts

Filed July 22, 1963, Ser. No. 75,895

Term of patent 14 years

(Cl. D58—26)

FIG. 1.

FIG. 2.

FIG. 3.

FIG. 4.

FIG. 5.

FIG. 6

FIG. 8

FIG. 10

FIG. 7

FIG. 9

FIG. 11

FIG. 13

FIG. 15

FIG. 12

FIG. 14

FIGURE 1 is a front elevational view of a dispensing top showing my new design wherein the top is circular;

FIGURE 2 is a top plan view thereof;

FIGURE 3 is a right side elevation thereof;

FIGURE 4 is a rear elevation thereof;

FIGURE 5 is a left side elevation thereof;

FIGURE 6 is a front elevational view of a dispensing top showing a modified form of my new design wherein the dispensing spout is located on the short axis of an ellipse;

FIGURE 7 is a top plan view thereof;

FIGURE 8 is a right side elevation thereof;

FIGURE 9 is a left side elevation thereof;

FIGURE 10 is a rear elevation thereof;

FIGURE 11 is a front elevational view of a dispensing top showing a modified form of my new design wherein the dispensing spout is located on the long axis of an ellipse;

FIGURE 12 is a top plan view thereof;

FIGURE 13 is a right side elevation thereof;

FIGURE 14 is a left side elevation thereof; and FIGURE 15 is a rear elevation thereof.

The fragmentary showing of the container in broken lines is for illustrative purposes only.

I claim:

The ornamental design for a dispensing top, substantially as shown and described.
